UNITED STATES PATENT OFFICE.

JOSEPH W. STEELMAN, OF PHILADELPHIA, PENNSYLVANIA, ASSIGNOR TO JOHN C. HARRIGAN, OF CAMDEN, NEW JERSEY.

VENTILATING-WASHER FOR KNIFE-BLADE FUSES.

1,173,889.

Specification of Letters Patent. Patented Feb. 29, 1916.

Application filed January 27, 1915. Serial No. 4,685.

To all whom it may concern:

Be it known that I, JOSEPH W. STEELMAN, a citizen of the United States, residing at Philadelphia, in the county of Philadelphia and State of Pennsylvania, have invented 5 certain new and useful Improvements in Ventilating-Washers for Knife-Blade Fuses, and I do hereby declare the following to be a full, clear, and exact description of the 10 invention, such as will enable others skilled in the art to which it appertains to make and use the same, reference being had to the accompanying drawings, and to the letters and figures of reference marked thereon, which form a part of this specification. 15

This invention relates to new and useful improvements in fuse cartridges and it relates more particularly to the provision of means for ventilating any type of fuse 20 which is commonly known as knife-blade fuses.

To this end and to such others as the invention may pertain, the same consists in the novel construction and in the peculiar 25 arrangement, combination and adaptation of parts, all as will be more fully hereinafter described, shown in the accompanying drawings and then specifically defined in the appended claims.

30 My invention is clearly illustrated in the accompanying drawings which, with the numerals of reference marked thereon, form a part of this specification and in which:—

Figure 1 is a side elevation of a refillable 35 knife-blade fuse cartridge of the type to which my invention is applied. Fig. 2 is a vertical central longitudinal section of the same. Fig. 3 is an end view of the cap removed. Fig. 4 is a plan view of the inner 40 side or face of the ventilating washer, and Fig. 5 is a plan view of the fusible connecting strip.

Reference now being had to the details 45 of the drawings by numeral, 1 represents the tubular body portion of the cartridge, the same consisting of a tube composed of suitable insulated material and having the inner surface at its opposite ends flared outwardly as shown at 2, the recessed ends being 50 designed to receive a pair of conical wedge-shaped blocks 3, disposed within the

conical opening provided by the outward flaring recess formed for their reception within the ends of the tube. The office of these blocks is to engage between them the 55 ends of the fusible strip 4 and serve to hold said strip in position. 5, 5 designate open-ended screw-threaded caps which are internally threaded to engage the external threads upon the outer ends of the face of 60 the cartridge. 6 is a metallic disk to the outer face of which is secured the knife-blade extension 7 and the opposite face 8 of the disk, which face, when the disk is in use, contacts with the end faces of the 65 blocks 3, 3, is provided with a circular groove 9 and provided at intervals and communicating with the groove are ventilating openings 10, 10.

It will be noted that the ends of the fusible strip being retained between the sections 3 of the conical blocks allows a slight space between the blocks and at the ends of the strip, whereby ventilation from the interior of the fuse to the under face of the disk 8 70 75 is provided. This space, communicating as it does with the circular groove 9 upon the inner face of the disk 6, permits free ventilation through the openings 10, 10.

Having thus described my invention, what 80 I claim to be new and desire to secure by Letters Patent is:—

A knife blade fuse cartridge comprising a hollow cylindrical cartridge circumferentially threaded, the inner surface of which 85 near its ends flares outwardly, conical-shaped clamping blocks engaging said flaring surfaces, a fuse clamped by said blocks, slotted caps fitted over the threaded portion of said cartridge, metallic disks having 90 blade extensions passing through said slots, said disks being held by the caps against the ends of the conical-shaped blocks, the inner face of each disk having a circumferential groove with vent openings therein. 95

In testimony whereof I hereunto affix my signature in presence of two witnesses.

JOSEPH W. STEELMAN.
